UNITED STATES PATENT OFFICE.

CHARLES M. CLARKE, OF SEWICKLEY, PENNSYLVANIA.

SUPPORT FOR TELEPHONE-RECEIVERS.

1,391,370.

Specification of Letters Patent. Patented Sept. 20, 1921.

Application filed August 13, 1918. Serial No. 249,735.

To all whom it may concern:

Be it known that I, CHARLES M. CLARKE, a citizen of the United States, residing at Sewickley, in the county of Allegheny and 5 State of Pennsylvania, have invented certain new and useful Improvements in Supports for Telephone-receivers, of which the following is a specification.

My invention consists of an improvement 10 in telephones and has for its object to provide means whereby the receiver of the instrument may be removed from the usual supporting fork or bracket, and then replaced in registering position therewith so 15 as to remain inoperative for a predetermined period, and to then assume its normal pendant position, in order to obviate the necessity of waiting to replace the receiver in the fork after the call has been answered 20 over another instrument.

It frequently happens, in the use of telephones, where one or more branch lines are in circuit, that a call is received over the line through one of several instruments by 25 a party who then finds it necessary to call another part to answer the call through another of the instruments, as for instance, in a branch office, or at a different floor or location in a residence or other building.

Wherever delay occurs, as is frequently the case, it is either necessary for the party who first answers the call to remain at the instrument and then replace the receiver thereon after the other party has commenced 35 conversation, in order to prevent the closing of the circuit, or else, as frequently happens, the receiver is set down on a table or elsewhere and may not, through inadvertence, be replaced for some considerable time 40 thereafter. This results in leaving the entire system disarranged because of the open circuit, and results in the failure of the instrument to receive further calls until the receiver is replaced and the supporting fork 45 is depressed.

The invention consists in means for temporarily supporting the receiver in such a position as to allow it, when eventually lowered, after a desired postponement, to effect 50 downward pressure on the supporting fork, finally reaching its ultimate normal pendant position and reestablishing the "call" circuit.

In the drawings, which show one preferred 55 embodiment of the invention,

Figure 1 is a view in elevation, partly in

section, showing the device in inoperative position, with the receiver in pendant position on the fork:

Fig. 2 is a similar view showing the device 60 when raised to support the receiver and with pressure relieved from the fork;

Fig. 3 is a plan view of Fig. 1; and

Fig. 4 is a partial sectional view showing 65 a modified construction.

In the drawings, 2 represents the main stem or body of the instrument having at its upper portion the usual transmitter 3 and provided with the receiver-supporting and current-controlling fork 4, of well known 70 construction. The receiver 5, which normally hangs pendant in the fork, is adapted to be temporarily supported with its shouldered terminal fork-engaging portion 5^a in register with, but not resting on the 75 fork, by a suitable supporting device, as a pan or bracket 6.

Such bracket, as shown, is designed to receive the projecting ear terminal of the receiver within a surrounding upwardly 80 turned edge portion for greater security, and to insure alinement of the receiver with the fork, although the retaining edge of the bracket is not absolutely necessary.

Bracket 6 is designed when inoperative, to remain in a lowered position out of contact with the receiver, as indicated in Fig. 1, and to be thrust upwardly when used, to support the receiver sufficiently high that its other end is maintained away from gravitating 90 contact with the fork for a limited period of time, as indicated in Fig. 2. Bracket 6 is designed to gradually lower by the escape of air, or friction, or spring action, or other resistance interposed in any other suitable manner so that during a predetermined period, as say one minute, it will travel downwardly, allowing the receiver to also fall at the same rate and to come into contact with and depress the fork, remaining 95 thereafter in such normal pendant position 100 until again used.

For such purpose I have provided, in the particular embodiment of the invention disclosed, an air cylinder 7 secured by any 105 suitable means as a strap 8 to the vertical stem of the instrument 2, and containing the plunger 9. Said plunger is secured to the inner end of a stem 10 which extends downwardly through the bottom head 11 of 110 the cylinder, and preferably through a stuffing box having a tightening and loosening

gland 12. Bottom head 11 is provided with one or more air circulation ports 13 and a valve 14 which may be of thin rubber or other suitable material, with an air circulation opening 15 around stem 10. The stem extends downwardly through such stuffing box and may be off-set, as indicated, for clearance and is secured to the bracket 6 by nuts or otherwise, as indicated at 16.

10 Plunger 9 is so constructed, as my means of a suitable packing ring, as to make a practically air-tight fit within the holding cylinder 7 and a spring 17 is preferably interposed between the top of the plunger and 15 the top head 18 of the cylinder. Bracket 6 may be thrust out of register with the receiver, in the manner indicated in Fig. 3, or it may be merely left in its registering position without interference with the receiver.

15 In operation, bracket 6 is thrust upwardly by the hand, whereupon the space within the cylinder 7 will be filled with atmospheric air by suction, passing upwardly through 20 the central opening in flexible valve 14. When raised to its uppermost limit, as indicated in Fig. 2, valve 14 will then re-seat itself, effectively cutting off the outlet of air, except by the restricted flow through 25 the stuffing box or because of such slight leakage as may be provided.

30 The receiver 5 may then be set upon bracket 6 with its upper end 5^a projecting well above the bearing edges of receiving fork 4, and gradual escape of the air within the cylinder admits of gradual lowering of the plunger 9 either with or without spring 17, finally arriving at the bottom of the cylinder, as in Fig. 1, and leaving the receiver in supported position on the fork.

35 The time of downward travel of the receiver may be easily graduated, for a longer or shorter period, as desired, by controlling the outflow of air, as by tightening or loosening the gland 12, or in any other suitable manner.

40 If preferred, the device may be so constructed as to thrust a support, operable as the equivalent of bracket 6, upwardly underneath the shank portion of receiver arms 4, such pressure being gradually released in the same manner as above described, in which case, the receiver may be merely reinserted in the fork, which will thus be 45 gradually lowered under the depressing weight of the receiver with the same resulting effect. Such adaptation of the invention may be easily effected by merely continuing the stem 10 upwardly of plunger 9 so that when raised, it will pass upwardly 50 through an opening in cylinder head 18 and into abutting contact with the lower side of fork 4, as indicated at 10^a, Fig. 4. The main stem 10 extends downwardly 55 through the bottom of cylinder 7, as in the

main figures and provides means for thrusting the plunger upwardly. The release of air in such case may be controlled according to the reduced downward travel and greater leverage of the receiver through the 70 fork itself, inasmuch as the weight of the receiver is at once active upon the fork without the initial lost motion travel provided for in the first described construction.

75 The device may be variously changed or modified by the skilled mechanic in different details of construction or otherwise, but all such changes are to be considered as within the scope of the following claims.

80 What I claim is:

1. In a telephone set, normally inoperative manually adjustable means for temporarily suspending the normal gravitating action of the receiver fork and its supported receiver and for interposing a retarding resistance thereto whereby to effect a delayed lowering movement of the fork and receiver consisting of a holder mounted on the set and a movement retarding resistance 90 device therein.

2. In a telephone set, normally inoperative hand actuated mechanism for temporarily suspending the normal gravitating action of the receiver fork and its supported receiver and for automatically effecting a retarded movement thereof to delay the downward movement of the fork and receiver consisting of a holder mounted on the set and a movement retarding resistance 100 device therein.

3. A device of the class described consisting of a holder and a normally inoperative temporary supporting device therein capable of being thrust upwardly by the operator to temporarily support and resist gravitation of the receiver when in depressing position in the fork and having means for causing the supporting device to gradually recede and withdraw resistance therefrom. 110

4. A resistance mechanism for telephone receivers having a portion adapted to resist the weight of the receiver and maintain it in non-depressing relation to its supporting hook and to gradually allow the receiver to 115 overcome such resistance and to depress the hook.

5. Means for temporarily supporting a telephone receiver in operative relation to its supporting fork and for lowering it 120 thereinto, having a supporting device and means for interposing a decreasing resistance thereto.

6. Means for temporarily supporting a telephone receiver in operative relation to 125 its supporting fork and for lowering it thereinto, having a supporting device adapted to be thrust upwardly to supporting position, and means for gradually lowering the supporting device.

7. A receding support for a telephone receiver having means adapted to maintain the receiver in operative relation to its supporting fork and to temporarily oppose a gradually diminishing supporting resistance thereto. 40
8. A receding support for a telephone receiver having means adapted to maintain the receiver in operative relation to its supporting fork and to temporarily oppose a gradually diminishing supporting resistance thereto and to finally lower the receiver and fork to normal pendant position. 45
9. A receding support for opposing the weight of a telephone receiver and its fork when in supporting engagement consisting of a pneumatic cylinder having a plunger, a plunger stem having a terminal supporting portion adapted to oppose downward movement of the receiver and fork, and means providing for free inflow and restricted outflow of air to and from the cylinder. 50
10. A receding support for opposing the weight of a telephone receiver and its fork when in supporting engagement consisting of a pneumatic cylinder having a plunger, a plunger stem having a terminal supporting portion adapted to oppose downward movement of the receiver and fork, a valve providing for free inflow of air to the cylinder and adapted to close against outflow of air therefrom, and means for graduating the exhaust of air to effect gradual lowering of the plunger. 55
11. A weight resisting device for a telephone receiver and its fork when in supporting engagement consisting of a pneumatic cylinder having a plunger, an air inlet and outlet controlling valve for the cylinder, means for graduating outflow of air, and a stem connected with the plunger having a portion adapted to oppose gravitating action of the telephone receiver. 60
12. A weight resisting device for a telephone receiver and its fork when depressed thereby consisting of a pneumatic cylinder having a plunger, an air inlet and outlet controlling valve, means for graduating outflow of air, and a stem connected with the plunger having a portion adapted to engage and support the receiver. 65
13. A weight resisting device for a telephone receiver and its fork when depressed thereby consisting of a pneumatic cylinder having a plunger, an air inlet and outlet controlling valve, means for graduating outflow of air, and a stem connected with the plunger having a portion adapted to engage and support the receiver and to be thrust out of register therewith. 70
14. A weight resisting device for a telephone receiver and its fork when in supporting engagement consisting of a pneumatic cylinder having a plunger, an air inlet and outlet controlling valve, means for graduating outflow of air, a stem connected with the plunger having a portion adapted to engage and support the receiver and arranged to be thrust upwardly to raise the plunger, and a spring adapted to assist in depressing the plunger and its stem. 75

In testimony whereof I hereunto affix my signature.

CHARLES M. CLARKE.

It is hereby certified that in Letters Patent No. 1,391,370, granted September 20, 1921, upon the application of Charles M. Clarke, of Sewickley, Pennsylvania, for an improvement in "Supports for Telephone-receivers," errors appear in the printed specification requiring correction as follows: Page 1, line 26, for the word "part" read *party*; page 2, line 10, for the word "my" read *by*; and that the said Letters Patent should be read with these corrections therein that the same may conform to the record of the case in the Patent Office.

Signed and sealed this 20th day of October, A. D., 1921.

[SEAL.]

WM. A. KINNAN,

Acting Commissioner of Patents.
